CLAIM

The ornamental design for a terminal and stand, as shown and described.

DESCRIPTION

FIG. 1 is a general perspective view of a terminal and stand showing our new design;
FIG. 2 is a top view thereof;
FIG. 3 is a leftside view thereof;
FIG. 4 is a rightside view thereof;
FIG. 5 is a rear view thereof; and,
FIG. 6 is a front view thereof.
The bottom of the stand is flat and unornamented.
